UNITED STATES PATENT OFFICE.

GEORGE N. BARCUS AND CLARENCE E. SMITH, OF WABASH, INDIANA, ASSIGNEES TO THE ROCK CITY MANUFACTURING COMPANY, OF WABASH, INDIANA, A CORPORATION OF INDIANA.

MACHINE FOR ASSEMBLING SPRING-HINGES.

1,137,451.

Specification of Letters Patent. Patented Apr. 27, 1915.

Application filed July 16, 1914. Serial No. 851,327.

To all whom it may concern:

Be it known that we, GEORGE N. BARCUS and CLARENCE E. SMITH, citizens of the United States, residing at Wabash, Wabash county, and State of Indiana, have invented and discovered certain new and useful Improvements in Machines for Assembling Spring-Hinges, of which the following is a specification.

10 Our invention relates to machines for assembling spring hinges and its object is to provide an effective and easily operated construction capable of putting together by machinery the separate parts of a spring hinge.

15 With this object in view our invention is embodied in preferable form in the machine hereinafter described and illustrated in the accompanying drawings.

In these drawings, Figure 1 is an end view 20 in elevation of a machine embodying our invention; Fig. 2 an enlarged side view in elevation; Fig. 3 a section on the line 3—3 of Fig. 2; Fig. 4 a vertical section on the line 4—4 of Fig. 1; Fig. 5, a vertical section 25 on the line 5—5 of Fig. 4; Fig. 6 an enlarged detail vertical section also on the line 5—5 but showing the spring pressed down into engagement with the hinge; Fig. 7, a similar view showing the plunger bearing 30 against the spring and showing the spring carrying jaws retracted to their normal position; Fig. 8, a section on the line 8—8 of Fig. 7; Fig. 9, a section on the line 9—9 of Fig. 5; Fig. 10, a section on the line 10—10 35 of Fig. 5.

Referring to the drawings, 1 is the rigid supporting base of the machine and 2 an upright standard extending therefrom. A treadle lever 3 is pivoted at the upper end 40 of this base and connected to the rear arm thereof is a return spring 4. To the rear end of this lever is pivoted the lower end of a rod 5, the upper end of which is connected to a rocking beam 6 which is centrally pivoted in the upright 2. The forward end of 45 this rocking beam is pivoted to a vertically sliding frame 7 which is adapted to slide through and is guided by brackets 8 and 9 which are rigidly clamped on the upright 2. This sliding frame is provided at its lower 50 end with a fixed plunger or ram 10, the lower edge of which is curved in order to adapt it to receive a spiral spring 11 which is to be applied to the hinge. One longi-

tudinal edge 12 of this plunger is prolonged 55 into a lip projecting beyond the opposite edge which lip serves as a stop to limit the downward movement of the plunger by contact of said lip with one of the hinge members 13. The plunger constitutes means for 60 forcing the spring into its proper position on the hinge members and imparting a tension to the spring while so positioning it. This plunger extends between and is movable relatively to jaws 14 and 15 which are 65 hung upon bolts 16, 16 extending longitudinally through a head 17. This head is hung on vertical rods 18 which project upwardly through openings formed in the clamp member 9. The upper end of each rod is 70 provided with an adjustable nut 19 which is adapted to bear upon the upper end of a spiral cushion and return spring 20. This return spring surrounds a hollow sleeve 21 through which the rod passes and which 75 sleeve is fixed in the clamp member 9 so that when the jaw-carrying head 17 moves downwardly the nuts on the ends of the rods 18 will bear against the springs, compressing 80 said springs and permitting the downward movement of the head to continue until the nuts strike against the upper ends of the fixed sleeves 21, whereupon the descending movement of the jaws will be stopped, while the plunger will continue to move downward relatively thereto. 85

The jaws 14 and 15 are provided on their lower edges with opposite, longitudinal, inwardly projecting horizontal ledges 23 and 24 respectively. The ledge 23 of the jaw 14 is 90 shorter than that of the opposite jaw for the purpose of permitting the jaw 14 to take over upon a projecting portion of the particular kind of hinge which is illustrated in the drawing as one form of a spring hinge, 95 although it is, of course, obvious that the machine may be used with hinge members of other forms and is not confined to a jaw having the cut-out portion to accommodate the same to the particular hinge member illustrated. The jaws 14 and 15 are provided at opposite ends with inwardly projecting vertical retaining plates 25 against which the opposite ends of the spiral spring of the hinge member are adapted to abut and 100 whereby these ends are retained in place in the jaws until the spring has been discharged upon the hinge. Bolted to the ex-

terior faces of the jaws are upwardly extending guide arms 26 and 27, the arm 26 being pivoted at its upper end to a bar 28 which extends transversely through a slot 29 formed in the frame 7. The other arm 27 is provided with a slot 30 which engages the bar 28 so as to permit a sliding movement of the arm thereon.

The spiral spring of the hinge member is placed within the jaws when the latter are in their raised position and the ends thereof rest upon the ledges 23 and 24. As the frame 7 is forced downwardly the jaws 14 and 15 will be stopped in their downward movement by the abutment of the nuts 19 against the upper ends of the sleeves and the plunger will continue downwardly exerting a pressure against the spring which will force the jaws laterally apart. In order to guide the free ends of the hinge spring within the upwardly projecting end flanges or ears 31 of the hinge members, the jaw 14 is adapted to be given a sliding movement parallel to the axis of the spring in order to pull the end of the spring inwardly so that it may clear the said ears. This movement is effected by a plate 32 carried by the bolt 16 on which the jaw is mounted and having an inclined cam slot 33 which engages with a pin or set screw 34 fixed to the clamp member 9, whereby as the jaws are carried downwardly, the jaw 14 will be given a slight inward movement parallel to the axis of the spring, such as will carry its end plate 35 against the spring and thus pull the end of the spring within the inner edge of the ears of the hinge.

The hinge members 13 are adapted to be placed upon an anvil 35 in position to receive the spring and a rivet which passes through the spring and through the usual ears of the hinge members and which serves to connect said members and to constitute the pivot thereof. The hinge members are held in correct position on this anvil with the apertures in their ears held in register by means of guide plates 36 and 37, fixed on the upper face of the anvil. After the spring has been seated on the hinge members the rivet 38 is passed through the openings in the ears of the hinge members and through the spring and then the inner end of this rivet is upset by the operation of manually controlled mechanism. This mechanism consists of a vertically slidable backing plate 39 which is movable in guides in the base 1 and which is adapted to be moved upward beyond the head of the rivet in order to form a backing therefor against which pressure may be exerted when the opposite end of the rivet is to be upset. The lower end of this backing plate is pivoted to one end of a lever 40. This lever is fulcrumed on an ear 41, extending downwardly from the base of the machine and a

spring 42 connects the lever with the said base. The outer end of the lever extends freely between arms formed at the outer end of the base and against such free end on the upper edge thereof is adapted to bear a cam 43 carried by a shaft 44 which is provided with an operating lever 45. A return spring 46 is mounted on the shaft of this controlling mechanism. When the lever 45 is pulled downwardly from the position shown in Figs. 1 and 2, the shaft will be turned so as to carry the high part of the cam against the free end of the lever 43, thus rocking said lever on its fulcrum and lifting the backing plate 39 up to a position behind the head of the rivet. By the same movement the upsetting mechanism is moved into position to engage the opposite end of the rivet. To this end the shaft 44 has fixed thereto a forked member 47 of a toggle to which is pivoted the other member 48 of the toggle, the inner end of this member being forked and adapted to pivotally engage a collar 49 keyed on a sliding and rotatable shaft 50 which rotates within the collar. This shaft is movable longitudinally through bearing members 51 mounted on the base of the machine and carries at its outer end grooved upsetting rollers 52 and 53 with axes at right angles which are adapted to bear against and upset the inner end of the rivet in a manner well known in devices of this character. Keyed on the sliding shaft 50 is a driven pulley 54 which is adapted to be driven by a belt 55 which may be connected to any suitable source of power.

The operation of the machine is as follows:—The parts being in the position shown in Figs. 1, 2 and 5, the spring 11 of the hinge is inserted in place on the jaws 14 and 15, with the spirals of the spring bearing against the curved under face of the plunger 10 and with the free ends of the spring resting on the opposite ledges 23 and 24 of the jaws. In this position of the spring the latter will be relaxed and consequently the end portions will extend downwardly, crossing one another as indicated in Fig. 5. The hinge members 13 are placed on the anvil 35 and held in correctly alined position by means of the guide plates 36 and 37, the rivet openings through the ears 31 of the hinge members being in registry. The operator then depresses the foot treadle 3 which lifts the rod 5 and this action carries downwardly the frame 7 thus forcing down the plunger and the jaws. When the nuts 19 on the ends of the rods 18 fixed to the jaw head 17 come in contact with the upper ends of the sleeves 21, the downward motion of the jaws 14 and 15 will be arrested but the plunger will continue its downward movement thus exerting a pressure upon the coils of the spiral spring. This pressure will be

- transmitted through the free ends of the spring to the pivotally hung jaws thus gradually forcing them apart and spreading out the ends of the spring so that their direction 5 approaches a horizontal line and imposing a tension upon the spring. As this movement is continued the jaws will be forced so far apart that they will release the ends of the spring. This action takes place just as the 10 jaws and the spring reach the hinge members as indicated in Fig. 6. As the jaws are released, from the hinge spring 11, they will be retracted by their return springs 20 to their normal upper position. The plunger 15 meanwhile will continue its downward movement and will force the ends of the spring down upon the opposite members of the hinge, thus placing the spring on the hinge under tension. In this downward 20 movement of the jaws and plunger, the end plate 25 of the jaw 14 will carry said jaw laterally so as to force the outer end of the hinge spring within the outer ears of the hinge members.
- 25 The projecting lip 12 of the plunger serves to gage the downward movement of the plunger so that the cylindrical part of the spring will be brought in direct registry with the openings through the ears of the hinge 30 members. While the spring is held down against the upper surfaces of the hinge members the rivet 33 is inserted by hand through the apertures in the ears and through the coils of the spring as seen in Fig. 7. There- 35 upon the handle lever 45 is pulled downwardly which rotates the shaft 44 and actuates the toggle arm composed of the mem- bers 47 and 48 which action moves inwardly the shaft 50 so as to carry the upsetting roll- 40 ers 52 and 53 into engagement with the inner end of the rivet, whereupon as the shaft is rotated by the pulley 54, the rivet will be upset and clenched upon the ears of the hinge member. The handle lever is then re- 45 leased and is restored to normal position by means of the spring 46. The completed spring hinge member is then removed from the anvil and the machine is ready for another operation.
- 50 The machine above described enables the parts of a spring hinge member to be readily positioned and the spring to be subjected to tension, and spring and rivet to be applied with facility and rapidity.
- 55 Having thus described our invention, what we claim is:
1. In a machine for assembling spring hinge parts, means for supporting hinge members, movable means for forcing said hinge members and spring together and so that the eye of the spring will register with the perforations in the ears of the hinge and mechanism for operating said movable means, substantially as described.
  - 60 2. In a machine for assembling spring hinge parts, means for supporting hinge members, means for supporting a spring, means for moving said supporting means relatively toward one another and means for simultaneously forcing said spring from its supporting means against the hinge members with the spring eye in registry with the hinge pivot perforations and imparting tension to said spring, substantially as described.
  - 65 3. In a machine for assembling spring hinge parts, means for supporting hinge members, means for carrying a hinge spring, means for spreading the ends of the spring and means for moving said spring carrying means toward the hinge support, and means for forcing said spring from its carrying means against the hinge members and into a position in which the eye of the spring and the perforations in the ears of the hinge are in alinement, substantially as described.
  - 70 4. In a machine for assembling spring hinge parts, means for supporting hinge members, movable opposite yielding members adapted to receive and support the free ends of a spring, a member movable relatively to the spring supporting members, and operable to exert pressure in said spring to spread the spring ends and also the supporting member apart, and to carry said spring against said hinge members and the eye of the spring into registry with the perforations in the ears of said members, substantially as described.
  - 75 5. In a machine for assembling spring hinge parts, means for supporting hinge members, a hinge-spring carrier movable toward and from said supporting means and coöperating to operatively position the spring on said hinge members, opposed swinging jaws on said carrier adapted to receive respectively the opposite free ends of the spring, a plunger mounted on said carrier between said jaws and movable relatively thereto, said plunger having means to engage a spring and force it against the hinge members, means to limit the movement of said jaws relatively to the carrier, and means for operating said carrier, substantially as described.
  - 80 6. In a machine for assembling spring hinge parts, means for supporting hinge members, opposite pivoted members for receiving and supporting the respective ends of a spring, a carrier movable toward and from said supporting means and on which said pivoted members are mounted, coöperating with said supporting means for bringing the spring and hinge members together in operative relation, means fixed to the carrier for engaging said spring and movable beyond the limit of movement of said pivoted members to carry the spring therefrom and force it into operative position on the hinge members and means to automatically return
  - 85 7. In a machine for assembling spring hinge parts, means for supporting hinge members, means for supporting a spring, means for moving said supporting means relatively toward one another and means for simultaneously forcing said spring from its supporting means against the hinge members with the spring eye in registry with the hinge pivot perforations and imparting tension to said spring, substantially as described.
  - 90 8. In a machine for assembling spring hinge parts, means for supporting hinge members, movable opposite yielding members adapted to receive and support the free ends of a spring, a member movable relatively to the spring supporting members, and operable to exert pressure in said spring to spread the spring ends and also the supporting member apart, and to carry said spring against said hinge members and the eye of the spring into registry with the perforations in the ears of said members, substantially as described.
  - 95 9. In a machine for assembling spring hinge parts, means for supporting hinge members, a hinge-spring carrier movable toward and from said supporting means and coöperating to operatively position the spring on said hinge members, opposed swinging jaws on said carrier adapted to receive respectively the opposite free ends of the spring, a plunger mounted on said carrier between said jaws and movable relatively thereto, said plunger having means to engage a spring and force it against the hinge members, means to limit the movement of said jaws relatively to the carrier, and means for operating said carrier, substantially as described.
  - 100 10. In a machine for assembling spring hinge parts, means for supporting hinge members, opposite pivoted members for receiving and supporting the respective ends of a spring, a carrier movable toward and from said supporting means and on which said pivoted members are mounted, coöperating with said supporting means for bringing the spring and hinge members together in operative relation, means fixed to the carrier for engaging said spring and movable beyond the limit of movement of said pivoted members to carry the spring therefrom and force it into operative position on the hinge members and means to automatically return
  - 105 11. In a machine for assembling spring hinge parts, means for supporting hinge members, means for supporting a spring, means for moving said supporting means relatively toward one another and means for simultaneously forcing said spring from its supporting means against the hinge members with the spring eye in registry with the hinge pivot perforations and imparting tension to said spring, substantially as described.
  - 110 12. In a machine for assembling spring hinge parts, means for supporting hinge members, movable opposite yielding members adapted to receive and support the free ends of a spring, a member movable relatively to the spring supporting members, and operable to exert pressure in said spring to spread the spring ends and also the supporting member apart, and to carry said spring against said hinge members and the eye of the spring into registry with the perforations in the ears of said members, substantially as described.
  - 115 13. In a machine for assembling spring hinge parts, means for supporting hinge members, a hinge-spring carrier movable toward and from said supporting means and on which said pivoted members are mounted, coöperating with said supporting means for bringing the spring and hinge members together in operative relation, means fixed to the carrier for engaging said spring and movable beyond the limit of movement of said pivoted members to carry the spring therefrom and force it into operative position on the hinge members and means to automatically return
  - 120 14. In a machine for assembling spring hinge parts, means for supporting hinge members, opposite pivoted members for receiving and supporting the respective ends of a spring, a carrier movable toward and from said supporting means and on which said pivoted members are mounted, coöperating with said supporting means for bringing the spring and hinge members together in operative relation, means fixed to the carrier for engaging said spring and movable beyond the limit of movement of said pivoted members to carry the spring therefrom and force it into operative position on the hinge members and means to automatically return
  - 125 15. In a machine for assembling spring hinge parts, means for supporting hinge members, means for supporting a spring, means for moving said supporting means relatively toward one another and means for simultaneously forcing said spring from its supporting means against the hinge members with the spring eye in registry with the hinge pivot perforations and imparting tension to said spring, substantially as described.
  - 130 16. In a machine for assembling spring hinge parts, means for supporting hinge members, movable opposite yielding members adapted to receive and support the free ends of a spring, a member movable relatively to the spring supporting members, and operable to exert pressure in said spring to spread the spring ends and also the supporting member apart, and to carry said spring against said hinge members and the eye of the spring into registry with the perforations in the ears of said members, substantially as described.

said pivoted members to normal position independently of the carrier, substantially as described.

7. In a machine for assembling spring hinge parts, means for supporting hinge members, a hinge-spring carrier movable toward and from said means to position the spring operatively on said hinge members, swinging jaws mounted on said carrier and movable therewith and also having a limited movement in the same line independently of said carrier, a plunger mounted on said carrier between said jaws, means for forcing said carrier toward the hinge support to deposit the spring on the hinge and means for automatically moving the jaws away from said support independently of the plunger, substantially as described.

8. In a machine for assembling spring hinge parts, a support for the hinge members, a vertically movable hinge spring carrier above said support adapted to carry the spring and hinge members into operative relation, oppositely swinging jaws mounted on horizontal pivots on said carrier, said jaws having means to retain said spring and to respectively engage the opposite free ends of the spring, a plunger on said carrier having movements with and relative to the jaws and operable to press on the spring to force the same from the jaws and against the hinge members, means for moving said carrier toward the supporting means and means for automatically raising and closing the jaws independently of the carrier, when the spring is released from said jaws, substantially as described.

9. In a machine for assembling spring hinge parts, hinge spring retaining members pivoted to swing in opposite directions, and having opposite lateral ledges projecting toward one another, substantially as described.

10. In a machine for assembling spring hinge parts, means for supporting hinge members, a carrier for the hinge spring movable toward and from said supporting means to position the spring on the hinge members in operative relation thereto, oppositely swinging members adapted to respectively receive the opposite free ends of a spiral spring, means for forcing said members apart and moving said spring therefrom against the hinge members between the rivet ears thereof and means for moving an end of the spring longitudinally of the spring axis to clear said ears as the spring is positioned on the hinge, substantially as described.

11. In a machine for assembling spring hinge parts, a hinge support, a swinging hinge spring retaining jaw, having a horizontal longitudinal ledge at its lower edge and having a flange at the end of said ledge at right angles to the latter, means for moving the jaw toward the support to position the spring on the hinge members in operative relation thereto, and means for moving said jaw at right angles to said first movement to carry said flange against the spring, substantially as described.

12. In a machine for assembling spring hinge parts, means for respectively supporting the hinge members and a helical spring, means for moving said supporting means relatively toward one another to carry the spring and members together into operative relation, with the eye of the spring in registry with the perforations in the ears of the members, means for imparting tension to said spring as it is positioned and means carried by the machine for upsetting the hinge rivet and mechanism for operating said carrying and upsetting means, substantially as described.

13. In a machine for assembling spring hinge parts, means for forcing the hinge members and spring together into operative relation with the eye of the spring in registry with the perforations in the ears of the members, a rivet upsetting means movable toward and from the hinge members in a line at an angle to the line of movement of said forcing means, substantially as described.

14. In a machine for assembling spring hinge parts, a fixed anvil, means on said anvil to engage hinge members to hold them in registry, a helical spring carrier movable toward said anvil for positioning the spring on the hinge members in operative relation thereto, means for spreading the ends of said spring, means for operating said carrier, a rivet upsetting mechanism movable toward and from said anvil at right angles to the movement of the carrier and means for driving said mechanism, substantially as described.

In witness whereof, we have hereunto set our hands and seals at Indianapolis, Marion county, Indiana, this 10th day of July, A. D., nineteen hundred and fourteen.
